ELECTRIC SWITCH

William F. Steenweg, Milwaukee, Wis., assignor
to Allen-Bradley Company, Milwaukee, Wis., a
corporation of Wisconsin

Application September 15, 1934, Serial No. 744,099

9 Claims. (Cl. 200—166)

This invention relates to improvements in electric switches and refers more particularly to the contacts thereof.

In a copending application of Lynn H. Matthias, Serial No. 744,131, filed September 15th, 1934, the provision of means for preventing abnormal temperature rises at the contacts of an electric switch is disclosed. Such undesirable contact temperature rises are largely the result 10 of vibration at the contacts. Consequently, by preventing this vibration, the undesirable temperature rises are precluded.

In the aforesaid copending application, one manner of damping out these vibrations is disclosed, and while the means shown therein is effective, the present invention has as its broad general object to provide an improved and simplified means for preventing the objectionable vibration.

More specifically it is an object of this invention to combine this means with the regular contact pressure spring or in other words to provide a contact pressure spring which is so constructed that it inherently provides means for holding the movable contact against objectionable vibration when the switch is closed.

With the above and other objects in view which will appear as the description proceeds, this invention resides in the novel construction, combination and arrangement of parts substantially as hereinafter described and more particularly defined by the appended claims, it being understood that such changes in the precise embodiment of the hereindisclosed invention may be made as come within the scope of the claims.

The accompanying drawing illustrates one complete example of the physical embodiment of the invention constructed according to the best mode so far devised for the practical application of the principles thereof, and in which:

Figure 1 is a front elevation with parts broken away and in section illustrating part of a switch assembly and the application of this invention thereto;

Figure 2 is a cross section view taken through Figure 1 on the plane of the line 2—2; and

Figure 3 is a perspective view of the contact pressure spring.

Referring now more particularly to the accompanying drawing, the numeral 5 represents a terminal head formed of suitable insulating material and serving as a support for the stationary contacts 6.

In the present instance this terminal head is provided on its underside with a plurality of

separated arc quenching chambers or pockets 7, to the ceilings of which the sets of stationary contacts 6 are mounted. The mounting screws 8 which hold the contacts in place may be used to also mount terminals 9 and electrically connect the same with the contacts 6.

Each pair of stationary contacts 6 is adapted to be electrically bridged by a movable contactor 10 having contacts 11 fixed to its outer ends. All of the contactors 10 are mounted by means of 10 upstanding posts or studs 12, on an actuator bar 13 adapted to be moved by mechanism (not shown) to open and close the switch.

The contactors 10 are so mounted on their posts 12 as to have a degree of motion with respect to the actuator bar 13, which motion, when the switch is open and the contacts are disengaged, is taken up by compression springs 14 encircling the posts 12 and confined between the contactors and the actuator bar 13. Upon closure of 20 the switch and engagement of the contacts, the springs 14 are compressed and provide contact pressure.

With the conventional wire coil spring heretofore used, the contactor was free to rock or vibrate about an axis, which axis is longitudinal to the contactor and passes through the points of engagement of the contacts. This rocking motion or vibration, as more at length brought out in the aforesaid copending application, increases the contact resistance and results in an objectionable contact temperature rise.

This undesirable rocking motion or vibration on the part of the contactor or movable contact is best arrested by applying a mechanical force on 35 the contactor or movable contact in opposition to the force tending to produce the vibration; and in the aforesaid copending application, the opposing force is obtained by friction introduced by a spring finger engaging the contactor.

In the present invention, the force of friction is again utilized to oppose the force tending to produce the objectionable vibration, but without the addition of a separate spring member or its equivalent. Here an inherent attribute of the 45 novel spring used to afford contact pressure, provides the friction.

It is noted that the springs 14 are of the conical type and that their coils are composed of a flat ribbon so wound as to have intimate frictional 50 engagement with each other. This construction effectively precludes lateral flexure of the springs without in any wise interfering with the normal endwise expansion and contraction thereof, and inasmuch as the ends of the springs have firm 55

engagement with the contactors and the actuator bar, by preventing lateral flexure of the springs, the contactors are effectively held against vibratory rocking when the switch is closed.

The contact pressure springs thus have the dual function of preventing contact pressure and also damping out any tendency on the part of the movable contactor to vibrate.

10 What I claim as my invention is:

1. In combination, a pair of cooperating switch contacts, means mounting the contacts for engagement and disengagement, the meeting faces of the contacts being so shaped that the contact therebetween is restricted to a small area so that the contacts may rock on each other when engaged, and common means to provide contact pressure and cooperating surfaces engaged when the contacts are engaged to afford a force acting 20 on one of the contacts differently than the force providing the contact pressure to hold the same against rocking on the other contact.

2. In combination with a pair of cooperating switch contacts adapted to be engaged and disengaged, a coil spring urging one contact toward the other, the meeting faces of the contacts being so shaped as to have substantially a single point contact lying in a plane substantially coinciding with the axis of the spring so that the contacts may rock on each other to opposite sides of said plane when held together by spring pressure, and said spring incorporating means medially of its ends and including cooperating slidably engageable surfaces for offering 35 resistance to a tendency to rock in this manner.

3. In combination with two cooperating contacts adapted to be engaged and disengaged, a helical coil spring urging one toward the other, the meeting faces of the contacts being so shaped 40 that the contact therebetween is a restricted area so situated as to be cut by a plane coinciding with the axis of the spring so that the contacts may rock on each other to opposite sides of said plane when held together by spring pressure, and the convolutions of said spring having surfaces engageable while the spring is in compression and the contacts engaged for offering resistance to a tendency to rock in this manner.

4. In combination with a pair of cooperating 50 switch contacts adapted to be engaged and disengaged, a coil spring urging one contact toward the other, the meeting faces of the contacts being so shaped as to have substantially a single point contact lying in a plane substantially coinciding 55 with the axis of the spring so that the contacts may rock on each other to opposite sides of said plane when held together by spring pressure, and said spring having flat convolutions in frictional engagement so as to offer resistance to lateral flexure of the spring and thereby damp out any tendency of the contacts to rock in the manner set forth.

5. In a switch construction, spaced stationary contacts, rigidly connected movable contacts engageable with the stationary contacts to electrically bridge the same, a coil spring acting upon the movable contacts to urge the same toward the stationary contacts, the meeting faces of the contacts being so shaped that each cooperating set 70 of contacts has a very restricted area of engagement so situated that a given plane coinciding with the axis of the spring passes through both areas of engagement so that the connected movable contacts may rock on the stationary contacts, and the convolutions of said spring in-

corporating cooperating surfaces for offering resistance to a tendency on the part of the connected movable contacts to rock in this manner.

6. In a switch construction, spaced stationary contacts, rigidly connected movable contacts engageable with the stationary contacts to electrically bridge the same, a coil spring acting upon the movable contacts to urge the same toward the stationary contacts, the meeting faces of the contacts being so shaped that each cooperating set of contacts has a very restricted area of engagement so situated that a given plane coinciding with the axis of the spring passes through both areas of engagement so that the connected movable contacts may rock on the stationary contacts, and said spring having one end firmly supported and its other end firmly engaged with the connected movable contacts and having flat convolutions in frictional engagement so as to offer resistance to lateral flexure of the spring and thereby damp out any tendency on the part of the movable contacts to rock in the manner set forth.

7. In a switch construction, two spaced stationary contacts, two correspondingly spaced movable contacts, a bridging bar rigidly connecting the movable contacts, an actuator movably mounting said bar for moving the same so as to engage and disengage the movable contacts with the stationary contacts, said actuator including a coil spring supporting and yieldingly urging the bridging bar and consequently the movable contacts carried thereby toward the stationary contacts, the meeting faces of the contacts being so shaped that each cooperating set of contacts has a very restricted area of engagement so situated that a plane parallel with the line of motion of the movable contacts and passing through the restricted areas of engagement coincides with the axis of the spring so that the bridging bar and its movable contacts may rock on the stationary contacts to opposite sides of said plane, and said spring having slidably engageable cooperating surfaces providing means for offering resistance to a tendency on the part of the bridging bar and movable contacts to rock in this manner.

8. In a switch construction, two spaced stationary contacts, two correspondingly spaced movable contacts, a bridging bar rigidly connecting the movable contacts, an actuator movably mounting said bar for moving the same so as to engage and disengage the movable contacts with the stationary contacts, said actuator including a coil spring supporting and yieldingly urging the bridging bar and consequently the movable contacts carried thereby toward the stationary contacts, the meeting faces of the contacts being so shaped that each cooperating set of contacts has a very restricted area of engagement so situated that a plane parallel with the line of motion of the movable contacts and passing through the restricted areas of engagement coincides with the axis of the spring so that the bridging bar and its movable contacts may rock on the stationary contacts to opposite sides of said plane, and said spring having one end firmly supported and its other end firmly engaged with the bridging bar and having flat convolutions in frictional engagement so as to offer resistance to lateral flexure of the spring and thereby damp out any tendency on the part of the bridging bar and movable contacts to rock in the manner set forth.

9. In an electric switch, a plurality of spaced stationary contacts, a bridging bar having contact portions engageable with the stationary contacts, an actuator mounting the bar for movement to-

ward and from engagement with the stationary contacts, said actuator mounting the bridging bar so that the bar is free to adjust itself to the stationary contacts whereby the bar is free to rock 5 on its longitudinal axis, said actuator including a spring engaging and urging the bridging bar toward the stationary contacts to provide con-

tact pressure, and said spring incorporating means medially of its ends and including cooperating slidably engageable surfaces for offering resistance to a tendency of the bar to rock on its longitudinal axis without effectively interfering with the normal function of the spring. 5
